TOP FOR A CARRIER FOR BOTTLES OR THE LIKE

Kenneth D. Bixler, Huntington, and Robert E. Ralphs,
Katonah, N.Y., assignors to Diamond International Cor-
poration, New York, N.Y., a corporation of Delaware

Filed May 28, 1965, Ser. No. 85,505

Term of patent 14 years

(Cl. D58—26)

FIG. 3

FIG. 4

FIG. 5

FIG. 1 is a perspective view of a top for a carrier for bottles or the like showing our new design;

FIG. 2 is a top plan view thereof on an enlarged scale;

FIG. 3 is a side elevational view thereof;

FIG. 4 is an end elevational view thereof; and

FIG. 5 is a partial sectional view along lines 5-5 of FIG. 4.

The fragmentary broken line showing of a bottom portion of a carrier in FIG. 1 is for illustrative purposes only.

We claim:

The ornamental design for a top for a carrier for bottles or the like, as shown and described.
